2 Sheets-Sheet 2

FIG-6

The diagram illustrates a probe assembly. At the top, the text 'FIG. 7' is written above the number '39'. Below this, two long, thin, tapered rods are shown. The left rod is labeled with the number '18' near its tip. The right rod is labeled with the number '40' near its tip. The two rods are joined together at their bases. A horizontal line, labeled '62' at its right end, extends from the base of the rods. Below this line, a wavy line labeled '63' is shown, representing a flexible tube or coating. The entire assembly is labeled with the number '61' at its base.

UNITED STATES PATENT OFFICE.

SAMUEL DESURE, OF NEW YORK, N. Y.

ELECTRIC PRESSING IRON.

Application filed September 8, 1924. Serial No. 736,405.

To all whom it may concern:

Be it known that I, SAMUEL DESURE, a citizen of the United States, residing at New York city, in the county of New York and State of New York, have invented certain new and useful Improvements in Electric Pressing Irons, of which the following is a specification.

My invention relates to a new and improved electric pressing iron.

One of the objects of my invention is to provide an improved electric iron in which the heating element forms a separate unit so that it can be conveniently manufactured, and assembled with the other parts of the iron.

Another part of my invention is to provide a heating element comprising a plurality of separate heating coils, preferably not less than three which can be separately or simultaneously connected to a source of electric current, or connected in a large number of combinations, so that a sufficient number of variations of heat and working temperature can be secured.

Another object of my invention is to provide a heating element which extends over the entire iron, and has a plurality of separate heating coils, preferably not less than three, each coil occupying substantially the entire area of the element, so that the heating effect always extends over the entire area of the iron.

Another object of my invention is to provide a heating element having a series of coils so arranged that the maximum working temperature is never in excess of the temperature at which the wire of said coils remains substantially unaffected by the heat.

Another object of my invention is to provide a new and improved combination heating element and entering plug members, which can be made and handled as a unit.

Another object of my invention is to provide the handle of the iron with a plug device having entered plug members which cooperate with said entering plug members, so that the iron is made with a minimum number of parts, and no essential working parts are exposed.

Another object of my invention is to provide the handle of the iron with a plurality of switches for controlling the flow of the current to the coils of the heating element, so that the temperature of the iron can be conveniently controlled.

Other objects of my invention will be set forth in the following description and drawings, which illustrate a preferred embodiment thereof, it being understood that the previous statement of the general objects of my invention is made as a general explanation, and not as a limitation thereof.

Fig. 1 is an elevation.

Fig. 2 is an end view.

Fig. 3 is a top view.

Fig. 4 is a sectional view showing one of the handle switches and the connections thereof, the handle being shown as raised from its normal position.

Fig. 5 is a detail view partially in section, showing the handle switches and the plug construction.

Fig. 6 is a top view of the heater element.

Fig. 7 is a vertical central sectional view of the heater element.

Fig. 8 is a detail sectional view of the handle switch terminals. It is made on line 8—8 of Fig. 5.

Figs. 9 and 10 are diagrammatic views of the three heater coils shown in this embodiment.

As shown in Figs. 1-3, the iron has a bottom or pressing plate 1, which has bolts 15 and 16 secured thereto. The heating element, which will be later more fully described, includes coils of wire having upstanding terminal plug members, 19, 20, 52 and 53 shown in Fig. 6, and it is held between pressing plate 1 and a holding plate 3, which is provided with four holes at the front thereof, to permit the passage of said plug members 19, 20, 52 and 53. The holding plate 3 has two additional holes to permit the passage of bolts 15 and 16, and nuts 17 and 18 tightly clamp the holding plate 3 in position so that the heater element is tightly clamped between plates 1 and 3 and is prevented from shifting because said terminal members 19, 20, 52 and 53 project through the holes in clamping plate 3. The bolts 15 and 16 project through the cover 2, and the hood or cover 2 is clamped in position by nuts 14. The terminals 19, 20, 52 and 53 project through holes provided in the cover 2.

The handle 5 has at the front thereof a plug device 6 having four entered plug members which will be later more fully described, and when said handle 5 is in proper position, the terminal plug members of the

heater element enter the corresponding entered plug members provided for them in said plug member of handle 5.

The handle 5 is connected to the hood 2 by an arm 11, which is clamped against hood 2 by one of the nuts 14. The handle 5 is hollow and receives the cable C, having two conductors C' and C² which are connected to any suitable source of current. 10 The cable C is provided with a flexible metal protective tube 22, external to handle 5 and this protective tube 22 is clamped in the curve of arm 21 by means of screw 23. The arm 21 is clamped to handle 5 by the 15 hollow nut 12 through which cable C passes. The hollow nut 12 also clamps the upper end of arm 11 to handle 5.

The entire operative connection between handle 5 and the iron, for supporting the 20 weight of the iron, may be made at the rear of the iron by means of arm 11, because the slight frictional engagement between the terminals 19, 20, 52 and 53, and the corresponding plug members located at the front 25 of the iron, is so small that it produces no substantial grip between handle 5 and the iron. In fact, the plug device located at the front of the handle, could be made entirely separate therefrom without any difference 30 in operation of the iron. The handle 5 is made of any suitable strong insulating material, such as a phenol resin, etc. However, if the front nut 14 is tightened upon the bolt 15, this tightly clamps into position 35 the clamp member 4, which is later described, and which is connected to the plug device 6 by means of the screw 7. In this manner the handle can be firmly secured to the iron at both ends thereof.

40 The heater element, which is shown in detail in Figs. 6, 7, 9 and 10 comprises two mica coil plates 42 and 43, each which has substantially the shape and area of half the pressing plate 1, upper mica heater plates 45 47 and 48 connected to the coil plates 42 and 43 by the heating wire, and protective mica plates 46 and 49. The plates 46, 47, 48 and 49 have substantially the shape and area of the pressing plate 1, and the plates 46 and 50 49 are readily separable from the other mica plates before mentioned. The bottom protective plate 46 is perforated to permit the passage of bolts 15 and 16 and the upper protective plate is perforated to permit the 55 passage of terminals 19, 20, 52 and 53, and of bolts 15 and 16. The intermediate heater plate 47 and the upper heater plate 48 have perforations to admit said bolts 15 and 16 and the coil plates 42 and 43 have their adjacent edges recessed to permit the passage 60 of bolts 15 and 16. The upper heater plate 48 also has perforations corresponding to the terminals 19, 20, 52 and 53.

The adjacent and outer edges of the plates 65 42 and 43 are provided with uniformly ar-

ranged and equal slots or recesses S, to hold the windings of heating coils A, B, C.

The end of coil A is bent around the hole in plate 48, which corresponds to terminal 52. The wire is then led over plate 48, and 70 in close contact therewith, until it is passed through hole 70 to the underside of said plate 48. The wire is always kept in close contact with the plate, and this construction is followed in the other coils later mentioned. 75 The wire of coil A is then passed to the top of plate 48 through hole 71, then to the underside thereof through hole 72, and the wire is thus laced through plate 48 in this zig-zag manner through holes 73 and 74, so 80 that the first turn of coil A is formed on the underside of plate 42.

The coil A may be separated from coils B and C for a short portion of the rear of the heating element, and is passed around plate 85 42 in a spiral-like manner, the adjacent turns occupying the slots S, until the zone occupied by the coil B is reached. The coils B and C are then wound separately in alternate slots S, with their respective turns 90 separate, insulated from each other, and parallel, until the zone occupied by the coil C is reached. The coils A, B, and C have their respective turns then located in every third slot S, so that the turns of coils A, B, 95 and C are separated, insulated from each other, and parallel. The coil A is wound in this manner until the last three slots S in plate 42 are reached. The coil A is then carried over the top of companion coil plate 100 43. The windings of coil A are now continued reversely, to the rear of the companion coil plate 43. It will be noted that the upper portions of the respective turns of coils A, B and C are all parallel to each 105 other, and that the lower respective turns of said coils on plate 42 are parallel to each other, and that while the said lower turns on plate 43 are parallel to each other, that the lower turns on plate 42 and on plate 43 110 are oppositely inclined to the longitudinal axis of the heater element.

It will be noted that the plate 47 is imperforate, save at the rear thereof, where the wires of the heating coils are passed through it to be wound around coil plates 42 and 43. Hence what may be termed the laced or zig-zag portions of the coils are insulated from the turns of said coils. The heating wires connect the coil plates 42 and 43 to plates 47 and 48 so that a single connected structure is produced.

At the rear of coil plate 43, the wire of coil A is passed through plate 47 and plate 48 to the upper side of plate 48 and the wire is then led in zig-zag fashion as before mentioned, through holes in plate 48, until the end thereof is bent under said plate 48 at the hole corresponding to terminal 20. Hence the first and last portions of coil A 130

are above the plate 48 and the coil A will have a current passed through it, if the conductors C' and C² of cable C, are connected to terminals 20 and 52.

5 It will also be noted that while the coil A is behind coils B and C at the rear of plate 42, and coil B is behind coil C on plate 42, that the reverse relationship is found on plate 43. For convenience the turns of coil 10 A have been designated at the rear of Fig. 6 by a broken or "dash" line, while the turns of coil B have been designated by a full line, and the turns of coil A have been designated by a "dot and dash" line.

15 The first part of the wire of coil B is bent around the hole in plate 48 which corresponds to terminal 19, so that this first portion is located at the top of plate 48. The wire is then led to the underside of plate 48 through hole 55 and is then led through holes 57, 58, 59 and 60, and through plate 47, to the underside of plate 42. It may be noted that when the wire of coil A is led through hole 74, it is also passed 20 through plate 47 to the underside of plate 42. The wire is then wound as before mentioned and as shown in Fig. 6 until the last turn on coil plate 43 is completed and the wire is then led through plate 47 to the top 25 of plate 48. The wire is then passed in zig-zag fashion through plate 4, the last portion thereof being on the underside of plate 48, so that the end thereof is bent upwardly around the edge of the hole in plate 48 corresponding to terminal 20.

30 The first portion of coil C is on the upper side of plate 48, and its end is bent downwardly around the edge of the hole corresponding to terminal 53. The wire is then led in zig-zag manner through plate 48 until it is passed through plate 47 to the underside of plate 42. The coils are then wound as before mentioned and as 35 shown in Fig. 6 until the last turn on plate 43 has been completed, when the wire is passed through plate 47 and plate 48, to the upper side of plate 48. The wire of coil C is then led in zig-zag fashion through plate 48, so that the last portion thereof is 40 on the underside of plate 48, and its end is bent upwardly around the edge of the hole in plate 48 which corresponds to terminal 26.

45 Hence, each coil A, B, and C occupies substantially the same area. It is obvious that seven combinations of heating power can be supplied to the iron, so that it can be operated at seven distinct working temperatures. These combinations may be designated by the following, the respective letter or letters indicating the coil which is in circuit: A, B, C, AB, AC, BC, ABC. Any of the coils A, B, C can be placed in circuit, by connecting its terminals to cords C² 50 and C'.

Hence, even when a very high temperature is desired, there is no danger of burning out the wire, as in former devices in which high temperatures were secured by switching out portions of a heating coil, so 70 that the maximum heating effect was secured by very intensely heating a small length of wire which occupied only a small portion of the area of the iron.

With an iron about 7½ inches long and 75 having the contour shown in Figs. 1-3, which are drawn to scale, I prefer to make coils A, B, and C of substantially the same length, namely, 11½ feet and to form substantially 55 turns in each coil. The said coils A, B, C are made as long as is possible while maintaining proper insulation, since these coils are naked, and are insulated only by their spacing on the mica plates.

80 With the ordinary voltage of one hundred and ten (110) volts, I prefer to have coil A consume 170 watts, coil B consume 220 watts, and coil C consume 270 watts. If the wire of said coils is made of proper material, such as the nickel-chromium alloys now 85 on the market, it is never necessary to heat these coils beyond a temperature at which the wires have a straw color, and this temperature is so low, that the wire has very 90 long, practically perpetual life.

95 At the holes in plate 48 corresponding to terminals 19, 20, 52, and 53, the bent ends of the wires of said coils A, B, and C are engaged between the bases 63 of said terminals, and the bases 62 of socket members 100 61. These socket members 61, which are made of any suitable metal, have their body portions forced tightly into the hollow bodies of metal terminals 19, 20, 52 and 53 so that a firm frictional hold is secured and 105 satisfactory electrical connection is secured between the heating coils and the four terminals. The terminals are also firmly secured to plate 48 by said socket members 61, so that the entire heating element can be 110 handled as a unit, which facilitates assembling, inspection and repair work.

115 The switch mechanism adjacent handle 5 is shown in Figs. 4, 5 and 8, the various parts being located in suitable openings or recesses of the plug device 6 adjacent the front of handle 5.

120 The bottom of said plug device has four pairs of blades, each of the four terminals, 19, 20, 52 and 53 being adapted to pass between one of said pairs of blades, to be engaged by them for securing satisfactory electrical contact.

125 For convenience, that side of the iron which is at the left of a person holding the iron may be called the left side of the iron and this is the side shown in Fig. 5. A bent metal blade 35 is held in place by a nut 34, engaged by a suitable screw passing laterally through the plug device 6. The 130

blade 35 has a cooperating short blade 36. One end of cord C² is clamped by said nut 35, so that blade 35 is constantly connected to one terminal of the source of electric current.

Hence the terminal 20, whose reduced flat end 40 is clamped between blades 35 and 36 when the device is assembled, is always connected to said terminal of the current, and, 10 as can be seen in Fig. 6, one of the ends of each coil A, B, and C is always connected to one of the terminals of the current.

The blade 38 which corresponds to the reduced flat end 39 of terminal 19 has the 15 top 38' bent and passing through a hole in plug device 6 to the right side of said plug device. This blade 38 has a cooperating short blade 37.

The terminals 19, 20, 52 and 53 all have 20 the same contour, and terminals 52 and 53 are engaged by sets of blades similar to general construction to blades 35 and 36. Only blade 38 is bent so as to have the ends thereof at opposite sides of plug device 6, 25 as shown in Fig. 4. The long blade which engages terminal 52 is designated by 52' and the corresponding long blade for terminal 53 is designated as 53'.

As shown in Figs. 5 and 8, the conductor 30 C' is electrically connected to metal bar 32, by means of one of the three metal screws 33 which pass through plug device 6. Each of these screws 33 supports a separate angular metal switch member T at the right 35 hand side of plug device 6, each said member T being insulated from the others.

Hence the circuit is closed at the right side of plug device 6 as follows:—

The front switch makes contact between 40 front angular member T, which is electrically connected to C', and blade 52'. Hence terminals 20 and 52 are then connected, thus closing the circuit through coil A.

The middle switch makes contact between 45 middle angular member T, connected to C', and top 38' of blade 38. This connects terminals 20 and 19, thus closing the circuit through coil B.

The rear switch makes contact between 50 rear member T, connected to C', and blade 53'. Hence terminals 53 and 20 are connected closing the circuit through coil C.

Any ordinary snap switches may be employed in plug device 6. In this embodiment three separated guide members 28 may be located at the left side of plug device 6. These guide members support and guide the central portions 24 of the switch handles 8. These handles 8 are made of any suitable insulating material. The U-shaped switch levers 29 are respectively pivoted at 30 to plug device 6. Each lever 29 has a spring 30 connected thereto and the top of each spring 31 is connected to a central portion 65 24. The U-shaped levers 29 are resilient

and fit frictionally in the recesses in which they are located so that when a switch handle 8 is actuated, its spring 31 is tensed until it actuates its lever 29 with a snap act to fit firmly and with a frictional hold between 70 a terminal member T and one of the plug blades 52', 53', etc.

In Fig. 9, these switches are diagrammatically designated by S'.

It will be noted that when a plurality of 75 coils are put into the circuit, that they are in parallel, and in the preferred embodiment before mentioned, the power consumption in the various combinations is as follows:—A B 390 watts, A C 440 watts, B C 80 490 watts, A B C 660 watts.

This power consumption is very low for the working temperatures secured, in comparison with irons of known type.

While this invention could be used with 85 fewer or more than three heating coils, I prefer to use three coils, because two coils will not give the desired range of temperatures, and more than three coils are unnecessary for practical purposes. The switches, 90 blades, in plug device 6, and related parts are insulated by plates 41 which have holes through which members 8 can project. Plates 41 are held in position by a U-shaped 95 resilient clamping member 4, held in place by screws 7. The bottom of clamping member 4 has openings to permit the passage of the terminals 19, 20, 52 and 53.

I have shown a preferred embodiment of 100 my invention, but it is clear that numerous changes and omissions could be made without departing from its spirit.

It may be noted as an additional advantage of the construction before specified that the current carried by each coil 105 A, B and C is so small that no substantial or harmful sparking is produced when the circuit of each said coil is broken by one of the switches.

I claim:—

1. A heater element for electric irons comprising heating coil supporting means, a second insulating plate located adjacent said coil supporting means, the ends of the wire 115 on said coil supporting means being passed through said second plate, and a third insulating plate located adjacent said second plate and having the said ends of said wire passing therethrough, whereby said insulating plates and said coil supporting means 120 are connected by the heating wire.

2. A heater element for electric irons comprising a first insulating plate having the ends of a coil located thereon, the wire of 125 said coil being first laced in zig-zag manner through said plate, a second insulating plate adjacent said first plate, the said wire being led through said second plate after having been laced through said first plate, coil supporting means adjacent said second plate 130

around which said wire is wound after having been led through said second plate, said wire being then led back through said second plate at a point spaced from its first point of 5 passage, said wire being then laced through said first plate so that it is spaced from the first portion thereof on said first plate, whereby said two plates and said coil supporting means are connected by said wire, 10 said coil has two terminals on said first plate, and short circuiting is prevented.

3. A heater element for electric irons comprising a first insulating plate having both ends of a coil of wire thereon, said wire 15 being wound on coil supporting means, said coil supporting means being separated from said first plate by an intermediate insulating plate.

4. A heater element for electric irons comprising a first insulating plate having the ends of each of a plurality of coils of wire located thereon, the said ends of each said coil of wire being laced in zig-zag fashion through said plate so as to maintain the said 20 ends separated and insulated from each other, each of said coils having its windings formed on coil supporting means, and means to maintain the said windings insulated from each other and from the ends of the 25 said coils located on the first insulating plate.

5. A heater element for electric irons including an insulating plate having holes formed therein, the said plate having the ends of a coil located thereon and adjacent 30 the said holes, and terminals for the ends of said coil comprising upstanding recessed tubes having bases adjacent said plate, and of greater diameter than the said holes, and socket members adapted to enter and engage 35 the recessed portions of the said terminals, the said socket members having bases adapted to engage the said plate so that the said plate is clamped between the bases of the 40 said terminal members and of the said socket members and the ends of the said coil are 45 also clamped to the said insulating plate and are held in electrical contact with the said terminals.

6. A heater element for electric irons including three independent heating coils, each said heating coil being wound separately from the others on coil supporting means, and an insulating plate having the ends of the said coils connected thereto, the 50 said insulating plate also having terminals for the ends of the said coils connected thereto, one of the ends of each said coil being connected to a single common terminal and the other end of each said coils being 55 connected to an independent terminal.

7. A heater element for electric irons comprising a plurality of independent heating coils, the said coils being of substantially the same length and occupying substantially 60 the same area of the said iron.

8. A heater element for electric irons comprising a plurality of independent heating coils, each said coil having a series of windings on each side of the longitudinal axis of the iron, the windings of each said coil 70 on one half of the area of the iron being closer to the rear of the iron than the windings on the other half of the area of the iron, the positions of the rear portions of the windings of the said coils being reversed on opposite sides of the longitudinal axis of the iron.

9. A heater element for electric irons comprising three independent heating coils arranged in parallel, and switch means adapted to separately connect the said coils to a source of electric power, whereby seven heat gradations can be secured, the wattage taken by each said coil being insufficient to heat 80 the said coil to a temperature at which any substantial disintegration can take place, each said coil occupying a large and substantially the same area of the iron, and being adjacent the pressing plate of the said iron, whereby the heat produced by each 85 said coil is communicated substantially directly to substantially the entire pressing area of the said pressing plate.

10. An electric iron having a pressing plate and a heater element, a cover for said heater element, said heater element having terminals for the heating wire thereof projecting through said cover, and a plug device having blades adapted to separately contact with said terminals, said plug device being connected to said handle and movable therewith.

11. A device according to claim 10 having connecting means adapted to connect said iron to said handle, said connecting means being independent of and separate from said plug device.

12. An electric iron having a pressing plate and a heater element, a cover for said heater element, said heater element having three independent heating coils and having four terminals for the ends of said coils projecting through said cover, one of the ends of each said coils being connected to one of said terminals, the other end of each said coil being separately connected to one of the remaining three terminals and a plug device having three switches located therein, said plug device having four contact devices, each said contact device being adapted to contact with one of said terminals, one of said contacts having a terminal adapted to permanently connect it to one of the conductors of a cable, the contact adjacent the common contact having its top bent to the 110 opposite side of said plug device, said opposite side having three switch conductors adapted to be separately connected to the other conductor of said cable, and switches 115 adapted to separately connect the three ter- 120

minals other than said common terminal to said switch conductors, whereby the said switches cause the closing of the circuit through each said coil when they are in the same relative positions on said plug.

13. A device according to claim 12 in which the second mentioned conductor of the cable is connected to a metal bar by one of three metal screws which pass laterally through said plug device, each of said screws connecting one of said switch conductors to the plug device.

14. An electric iron having a pressing plate, a heater element, a cover for said

heater element, said heater element having 15 terminals adapted to project through said cover, a handle, a plug having contacts located in recesses thereof and adapted to engage said terminals, and a U-shaped clamp member adapted to engage said plug and 20 insulated from the conducting members therein, and means adapted to connect said clamp member to said plug and to the iron, said clamp member having a perforated bottom to permit the passage of said terminals. 25

In testimony whereof I hereunto affix my signature.

SAMUEL DESURE.
